CLAIM

The ornamental design for a molded mascara brush head with curved tree-shaped teeth, substantially as shown and described.

DESCRIPTION

FIG. 1 is a top, front and left side perspective view of our new design for a mascara brush head;

FIG. 2 is a top plan view of the mascara brush head shown in FIG. 1;

FIG. 3 is a bottom plan view of the mascara brush head shown in FIG. 1;

FIG. 4 is a left side elevation view of the mascara brush head shown in FIG. 1;

FIG. 5 is a right side elevation view of the mascara brush head shown in FIG. 1;

FIG. 6 is a rear elevation view of the mascara brush head shown in FIG. 1; and,

FIG. 7 is a front elevation view of the mascara brush head shown in FIG. 1.

The broken lines showing a partial stem rod illustrate environmental structure that forms no part of the claimed design.
